Primary Examiner — Michael C Stout*Assistant Examiner* — Fitzgerald L Butac(74) *Attorney, Agent, or Firm* — LUCAS & MERCANTI, LLP; Klaus P. Stoffel(57) **CLAIM**

The ornamental design for a DRILLING AID TOOL as shown and described.

DESCRIPTION

FIG. 1 is a top perspective view of a first embodiment of a DRILLING AID TOOL showing my new design;

FIG. 2 is a right side view thereof;

FIG. 3 is a front view thereof;

FIG. 4 is a left side view thereof;

FIG. 5 is a rear view thereof;

FIG. 6 is a top view thereof;

FIG. 7 is a bottom view thereof;

FIG. 8 is a top perspective view of a second embodiment of a DRILLING AID TOOL of the present invention;

FIG. 9 is a right side view thereof;

FIG. 10 is a front view thereof;

FIG. 11 is a left side view thereof;

FIG. 12 is a rear view thereof;

FIG. 13 is a top view thereof; and

FIG. 14 is a bottom view thereof.

The broken lines show portions of a Drilling Aid Tool which form no part of the claimed design.
